(57) **CLAIM**

The ornamental design for a docking station, as shown and described.

DESCRIPTION

FIG. 1 is a front perspective view of a docking station according to the present invention;

FIG. 2 is rear perspective view of the docking station;

FIG. 3 is a top view of the docking station;

FIG. 4 is a right side view of the docking station;

FIG. 5 is a left side view of the docking station;

FIG. 6 is a bottom view of the docking station;

FIG. 7 is a rear view of the docking station; and,

FIG. 8 is a front view of the docking station.

Broken lines shown in the drawings illustrate portions of the docking station and form no part of the claimed design.
